FIG. 3

FIG. 4.

This technical drawing illustrates a mechanical assembly, possibly a conveyor system, featuring a series of components arranged in a longitudinal perspective. Key labeled parts include:

- 21: A curved support or frame element.
- 24: A rectangular component positioned centrally.
- 30: A rectangular component located below the central assembly.
- 35: A rectangular component positioned above the central assembly.
- 36: A large rectangular component on the left side.
- 40: A rectangular component located to the right of the central assembly.
- 42: A component with a 'C' superscript, appearing in multiple locations.
- 44: A rectangular component positioned at the top right.
- 47: A rectangular component positioned below the top right component.
- 50: A component with a 'b' superscript, located near the center.
- 52: A component with a 'a' superscript, located near the center.
- 53: A component with a 'a' superscript, located near the bottom center.
- 56: A rectangular component positioned at the top left.
- 57: A rectangular component positioned at the top left.
- 59: A rectangular component positioned at the top right.
- 61: A rectangular component positioned at the top right.
- 8: A small rectangular component positioned at the top left.

UNITED STATES PATENT OFFICE.

JACOB FELBEL, OF NEW YORK, N. Y., ASSIGNOR TO UNION TYPEWRITER COMPANY, OF JERSEY CITY, NEW JERSEY, A CORPORATION OF NEW JERSEY.

TYPE-WRITING MACHINE.

No. 802,572.

Specification of Letters Patent.

Patented Nov. 3, 1908.

Application filed April 18, 1908. Serial No. 427,914.

To all whom it may concern:

Be it known that I, JACOB FELBEL, a citizen of the United States, and resident of the borough of Manhattan, city of New York, in the county of New York and State of New York, have invented certain new and useful Improvements in Type-Writing Machines, of which the following is a specification.

My invention relates to typewriting machines and more particularly to stop devices for arresting the platen at predetermined points in its rotation, the mechanism being devised more especially for use in preparing condensed record billing work.

15 The main object of the invention is to provide simple and efficient means of the character specified.

A further object of the invention is to provide stop devices which may be readily applied to existing forms of typewriting machines without modifying, or materially modifying, the structural features of said machines as they now exist.

To the above and other ends which will hereinafter appear, my invention consists in the features of construction, arrangements of parts and combinations of devices to be hereinafter described and particularly pointed out in the appended claims.

30 In the accompanying drawings wherein like reference characters indicate corresponding parts in the various views, Figure 1 is an end elevation and in section, on an enlarged scale, of part of a typewriting machine embodying my invention. Fig. 2 is an enlarged plan view of the same, showing in addition the parts which are sectioned away in Fig. 1. Fig. 3 is an enlarged detail sectional view taken transversely through 40 the stop carrying bar and chain and showing the chain and stop. Fig. 4 is an enlarged detail sectional view taken transversely through the stop carrying bar and showing the adjustable stop carried thereby.

45 Fig. 5 is an enlarged fragmentary end elevation of some of the parts shown in Fig. 2, the finger wheel being sectioned away in Fig. 5. Fig. 6 is an enlarged detail sectional view of the clutch and some of the 50 parts associated therewith, the section being taken longitudinally of the platen shaft. Figs. 7 and 8 are enlarged detail perspective views of the engaging members of the clutch. Fig. 9 is an enlarged detail sectional view of

the rear sprocket wheels and the adjustable support therefor. Fig. 10 is a detail front elevation with parts in section and parts broken away of a carriage equipped with the devices of my invention. Fig. 11 is a fragmentary detail plan view on an enlarged scale showing a different form of construction embodying my invention.

In the present instance I have shown my invention embodied in a Monarch typewriting machine to which the novel devices of my invention may be readily applied without materially modifying the regular structure of said machine.

The top plate 1 supports standards 2 to which fixed guide rails 3 are secured by screws 4. The rails 3 are oppositely grooved and receive anti-friction balls or rollers 5 which also run in opposite grooves 6 formed in a rear cross bar or traverse bar 7 constituting part of the paper carriage. Projecting forwardly from the back bar 7 are end bars 8, these several bars forming in the main the platen frame or carriage. A cylindrical rotative platen 9 is secured to a platen shaft 10 by a set screw 11 which enters a threaded hole in the hub of a right-hand platen head 12 and bears against the platen shaft. The platen shaft extends through and is journaled in bearing openings in the end plates 8 and is provided at its ends with finger wheels 13 and 14 secured to the platen shaft in the usual manner. The left-hand platen head is formed with line spacing ratchet teeth 15 thereon with which a spring-pressed roller detent 16 cooperates. A line spacing pawl 17 is pivoted to and carried by an arm 18 and co-acts with the line spacing wheel under the control of a finger piece 19 to effect a step-by-step line spacing movement of the platen. The right-hand end plate 8 of the carriage is formed with an upwardly extending arm 20 provided with a finger piece 21 by which the carriage may be moved to the right and by which it may be controlled when released from its spring drum for rapid movement toward the left. The parts thus far described are of the usual construction embodied in the Monarch typewriter and a further description thereof is deemed unnecessary.

105 The right-hand end of the platen shaft 10 where it extends beyond the platen frame is formed with a spline groove 22 in which

a spline 23 moves (Fig. 6). The spline 23 is secured to a clutch member 24 which surrounds the platen shaft and is provided with a peripheral groove 25. The clutch member 24 comprises an inwardly extending annular flange 26 and a single engaging or clutch tooth 27 which is arranged radially within the annular flange. The clutch member 24 also has an inwardly projecting hub 10 or sleeve 28 which surrounds the platen shaft and is itself surrounded by a coiled expansion spring 29 that bears at one end against the clutch member 24 and at its opposite end against the companion clutch member 30. The clutch section or member 30 is formed with an annular flange 31 provided with outwardly extending teeth 32 which are adapted to coöperate with the clutch tooth 27 on the member 24 and which 20 are preferably thirty-three in number corresponding to the number of teeth of the line spacing ratchet wheel. The purpose of this is to enable the clutch sections to be brought into proper position to engage no 25 matter what position the platen may be arrested in. The annular flange 31 surrounds the coiled spring 29 and is itself surrounded by the annular flange 26 on the clutch section 24. The clutch member 30 is provided 30 with an inwardly extending hub 33 which is loosely mounted on the platen shaft and to said hub is rigidly connected a sprocket wheel 34. This may be secured by a drive fit or by a set screw or otherwise.

35 From an inspection of Figs. 2 and 5 it will be observed that a bracket arm 35 is secured to the right-hand end plate of the platen frame by screws 36. A lever 37 is pivoted, on a shouldered headed screw 38, to the outer end of the bracket. The form of this 40 lever is best shown in Fig. 5 from which it will be seen that it is provided with a semi-cylindrical portion 39 contained within the circumferential groove 25 in the clutch section 24. This lever is provided with studs or rounded enlargements 40 and 41 which are situated upon opposite sides of the axis of the platen and are of a thickness or diameter corresponding substantially to the width 45 of the groove 25. The lever is prolonged at the upper portion thereof so as to provide a forwardly extending finger piece 42 by which it may be turned on its pivot to shift the clutch section 24 into and out of engagement with the companion clutch section 30. A leaf spring 42^a is secured by screws 42^b to the right-hand end plate of the carriage and extends beneath the lever 37. Two depressions or notches 42^c are 50 formed in this spring for engagement with the lever in either of the two positions to which it may be shifted; that is to say, in the position where an engagement is effected between the two clutch members or to the

position where the clutch members are dis- 65 engaged. The purpose of this spring is to hold the hand-lever and the parts controlled thereby against accidental displacement so as to maintain the clutch members either in or out of engagement, depending on the 70 position to which the lever 37 is moved, but if desired some other holding means may be employed. When the lever is in engagement with the inner notch 42^c the pressure of the spring 42^a is sufficient to overcome the 75 tension of the spring 29, the purpose of the latter spring being more particularly to assure disengagement between the clutch members when the finger piece 42 is moved to the right. In other words, the pressure ex- 80 ereted by the spring 29 is sufficient to prevent the clutch section 30 from moving along the platen shaft 10 to the right with the clutch section 24 when the latter is moved to the right to disengage it from the companion 85 clutch section. The movement of the clutch section 30 to the left is prevented by a hub 33 thereof bearing against a collar or sleeve 33^a (see Figs. 2 and 10) which forms part of the journal bearing in the right-hand end 90 plate of the carriage for the platen shaft and which is usually employed to take the end-wise thrust of the platen in the Monarch machine.

An endless band, flexible stop carrier, or 95 sprocket chain 43 coöperates with the sprocket wheel 34 and also coöperates with a sprocket wheel 44 pivoted or journaled on an eccentric or eccentric bushing 45. The eccentric 45 is provided with a hub 46 (see Fig. 9) 100 which bears at its inner end against the right-hand end plate 8 of the platen frame or carriage. A headed screw 47 passes horizontally through the eccentric and hub and engages at its threaded end in a threaded 105 opening in the right-hand end plate 8, the head of the screw overlapping the sprocket wheel 44 and retaining it in position on the eccentric 45, but without interfering with its free and independent rotation. The hub 110 of the eccentric is provided with a series of capstan openings 48 for use of a spanner wrench, pin or other suitable tool by which the eccentric may be turned on the screw 47 115 in order to adjust it and thus take up any slack that there may be in the endless band or chain 43. A set screw 49 extends through a threaded opening in the hub of the eccentric and bears at its inner end against the screw 47 to hold the eccentric in its adjusted 120 position. A stop 50 as shown in Figs. 1 and 3 is connected to the chain 43 in any suitable manner. In the present instance this stop is shown as substantially U-shaped in cross section and is connected to the chain by 125 pivots 51 which unite adjacent links of the chain. The U-shaped form of the stop 50 enables it to surround and slide along a stop

carrying supporting or guiding bar 52 which is secured at its ends to the platen frame or carriage.

The forward end of the bar is secured by 5 a screw 53 to a lug 54 which extends outwardly from the upwardly projecting arm 20 of the carriage. The other end of the bar 52 is secured by a screw 55 to a bracket 56 which in turn is secured to the carriage 10 by a screw 57. From an inspection of Fig. 1 it will be seen that the bar 52 has a portion thereof which is straight and extends parallel with the chain as the latter extends from one sprocket wheel to the other, and 15 that the rear end portion of the bar is curved downwardly so as to follow the curvature of the chain as it passes around the rear sprocket wheel. The bar carries a fixed stop 58 which is in the nature of a headed 20 screw. An adjustable stop 59 surrounds the stop bar on three sides (see Fig. 4) and has a threaded opening for the reception of a binding screw 60 provided with a knurled head 61 by which the stop may be secured 25 in any position along the stop bar to which said stop may be adjusted. A pin 62 extends through the inner wall of the stop and enters in a groove 63 which extends longitudinally of the bar throughout or substantially throughout the length thereof. This 30 pin prevents the adjustable stop 59 from becoming detached or being removed from the stop bar even when the binding screw 60 is released, but the pin 62 may be made in the form of a screw so as to permit ready detachment of the stop when desired. The stop bar is preferably provided with a scale or indices, the distance between the scale marks corresponding to a tooth space movement of 35 40 the line spacing ratchet wheel and platen as will hereinafter more clearly appear. It will be observed that in the present instance this scale extends to forty-two which is nine spaces more than that required to effect 45 a full revolution of the platen, it being presumed that there are thirty-three teeth of the line spacing ratchet wheel in the present instance. The purpose of this arrangement will hereinafter more clearly appear.

50 In the use of the machine for condensed record billing work the finger piece 42 is moved to the left to effect an engagement of the clutch members. The platen is then turned backwardly by either of the finger 55 wheels 13 or 14 until the chain stop 50 engages the fixed stop 58. An invoice or bill sheet is then introduced into the machine and the platen is rotated forwardly until it is in a position to receive the first line of writing 60 at, say, the date line thereon. During this forward rotation of the platen a backward rectilinear movement of the chain stop 50 takes place along the stop bar 51. If, for instance, it required a rotation of the platen

equivalent to twenty-five teeth of the line 65 spacing wheel to bring the bill to the proper position to receive the first line of writing, then the chain stop 50 would be moved to the graduation "25" on the stop bar. The adjustable stop 59 should then be adjusted to 70 contact with the chain stop 50 and the screw 60 should then be turned to secure the adjustable stop in this position. The platen should then be given a reverse or backward rotation by either of the finger wheels 13 or 14 until it is arrested by the engagement of the front face of the stop 50 with the fixed stop 58. The carbon and record sheet may then be introduced into the machine, the record sheet being next to the platen and the 75 carbon sheet being interposed between the invoice and record sheets. The platen may then be turned forwardly by either of the finger wheels 13 or 14 until it is arrested by the engagement of the rear face of the stop 80 85 50 with the adjustable stop 59. The finger piece 42 should then be moved to the right to release the clutch and the operator may proceed with the writing, the platen at this time turning independently of the stops, 90 chain and sprocket wheels. After the bill has been completed the operator may line space twice in order to provide for the proper spacing between the last line of the copy of the invoice just completed on the record sheet and the first line of the next manifold copy of the invoice to be written. The finger piece 42 should then be moved to the left to effect an engagement of the clutch members and the platen should be rotated 100 rearwardly by means of either of the finger wheels 13 and 14 until the stop 50 has been brought into engagement with the stop 58 and the platen is arrested. The invoice sheet may then be removed without disturbing the carbon and record sheets and a new invoice sheet may be introduced into the machine. The platen should then be turned forwardly until it is arrested by the contact of the chain stop 50 with the adjustable stop 105 59. The clutch should then be released and the writing proceeded with as before. In this manner carbon copies of successive bills or invoices may be made upon a condensed record sheet so that a large number of copies 110 115 of different bills or other matter may be made in condensed form or close arrangement on a single record sheet.

It will be observed that the construction is such that the stops enable the platen to 120 be turned more or less than a full revolution so that the device is capable of handling bill heads or invoice sheets of widely different characters; that is to say, bills varying from very short printed heads to very long 125 printed heads, and in which it may be necessary in some instances to turn the platen through more than a complete revolution in

1 order to bring the first line of writing on the invoice or bill sheet to the printing line.

Various modifications in the structure may be made without departing from the 5 spirit of my invention.

In Fig. 11 I have shown another form of construction in which the stop bar 52^a is straight throughout its entire length so that the chain stop 50^a will have only a rectilinear 10 ear movement back and forth. In this form of construction the chain stop is not carried by the bar 52^a but runs on or over a separate bar 64 arranged parallel with the stop bar. Moreover, the scale instead of being arranged on the outer side of the stop bar as in the construction shown in Fig. 1 15 is arranged on the top side of bar 52^a where it may be seen more readily by the operator. It will also be observed that in the form of 20 construction shown in Fig. 11 the relative adjustment between the fixed stop 58^a on the stop bar and the adjustable stop 59^a does not enable the platen to turn for more 25 than a complete rotation when the chain stop is operatively connected to the platen, the greatest range of movement of the chain stop corresponding to thirty-two spaces, slightly less than that necessary to permit 30 a complete rotation of the platen. However, this extent of movement will be found sufficient in most cases.

While I have described one method of using my devices and for setting them for condensed record work, it should be understood that the work may be performed in a 35 different manner.

In a front-strike or visible writing machine it may be necessary or desirable at times to arrest the platen during its backward rotation only. This may be done by 40 omitting or removing the stop 59, in which case the operator will note visually when the proper point on the invoice sheet has been brought to the printing line and then 45 he will release the clutch. The chain and the movable stop will be held frictionally in the positions to which they have been moved and when the bill is completed, the platen line spaced twice and the clutch engaged, 50 the platen may be given a reverse rotation and arrested in the proper position to receive a new invoice sheet.

From the foregoing description it will be seen that I have provided simple and efficient means for arresting the platen at pre-determined points in its backward and forward rotations and that these devices may be applied to existing forms of typewriting machines, such as the Monarch machine for 55 instance, without modifying or materially modifying the structural features of said machines and without interfering with the operation of the working parts already embodied in such machines; that the construc-

tion is simple in operation, and positive and reliable in use.

It will be observed that the platen, by means of its shaft and hand-wheels, is normally adapted to be rotated freely in either direction, that is, backwardly or forwardly; 70 that the sprocket wheels or band-wheels and chain or band are adapted to be connected with and disconnected from said platen at will by the operation of the clutch members; that when the platen is rotated in 75 either direction, and the chain or band wheels are connected therewith, the latter are caused to be rotated by the platen (or by the platen shaft which is practically the same thing) and the movable stop controlled 80 by the chain or band is caused to move simultaneously with the platen, and in unison therewith, and when said movable stop has been carried to the point where it engages with either of the relatively fixed stops, it, 85 together with its cooperating stop, causes the chain or band, the band wheels, platen shaft, and platen all to be arrested; that thereupon the band wheels and band and movable stop may be disconnected from the 90 platen by a reverse operation of the clutch, and that thereafter the platen may be freely rotated in either direction independently of the stop or arresting mechanism.

What I claim as new and desire to secure 95 by Letters Patent is:—

1. In a typewriting machine, the combination of a rotative platen, stops for arresting said platen, a chain for moving certain of said stops, and means for enabling the platen 100 to rotate independently of said stops.

2. In a typewriting machine, the combination of a rotative platen, stops for arresting said platen, a chain for moving certain of said stops, and means for operatively connecting said chain to and disconnecting it 105 from the platen.

3. In a typewriting machine, the combination of a rotative platen, stops for arresting said platen, means for effecting a relative 110 adjustment between certain of said stops, a chain for moving certain of said stops, and means for enabling the platen to rotate independently of said stops.

4. In a typewriting machine, the combination of a rotative platen, a platen frame, a chain, stops for arresting said platen, certain of said stops being held against movement on the platen frame and certain of them being moved by the chain, means for 120 effecting a relative adjustment between certain of said stops, and means which enable the platen to be turned to any desired extent without being arrested by said stops.

5. In a typewriting machine, the combination of a rotative platen, a platen frame, relatively adjustable stops carried by the 125 platen frame and held against movement

thereon, a chain, a stop fixed to said chain and adapted to move between said first mentioned stops to determine the extent of rotation of the platen, and hand actuated means operable at will for operatively connecting the chain to and for disconnecting it from said platen.

6. In a typewriting machine, the combination of a rotative platen, a platen frame, a bar carried by said platen frame, a stop which slides along said bar, a co-acting stop, and means for operatively connecting said sliding stop to and for disconnecting it from the platen, whereby rotation of the platen may cause the sliding stop to slide along said bar and whereby the platen may be rotated without transmitting movement to said sliding stop.

7. In a typewriting machine, the combination of a rotative platen, a movable stop that has a rectilinear movement, a coöperating stop, and means for operatively connecting the movable stop to the platen to be moved concurrently therewith, and for disconnecting said movable stop from the platen to enable the platen to be rotated indefinitely independently of said movable stop.

8. In a typewriting machine, the combination of a rotative platen, a platen frame, a movable stop that has a rectilinear movement, coöperating relatively adjustable stops carried by the platen frame, and means for operatively connecting the movable stop to the platen to be moved concurrently there-with between said relatively adjustable stops and for disconnecting said movable stop from the platen to enable the platen to move independently of said movable stop.

9. In a typewriting machine, the combination of a rotative platen, coöperating stops to arrest the platen, certain of said stops having a rectilinear movement and certain of said stops being relatively adjustable, and means whereby the stops are rendered inoperative to arrest the platen and the platen is left free to be rotated indefinitely.

10. In a typewriting machine, the combination of a rotative platen, coöperating stops to arrest the platen, certain of said stops having a rectilinear movement and certain of said stops being relatively adjustable to an extent to enable the platen to make more or less than a full revolution as may be desired before it is arrested by said stops, and means whereby the stops are rendered inoperative to arrest the platen and the platen is left free to be rotated indefinitely.

11. In a typewriting machine, the combination of a rotative platen, stops for arresting said platen after it has made more or less than a full revolution as may be desired, a chain for moving certain of said stops, and means for enabling the platen to rotate independently of said stops.

12. In a typewriting machine, the combination of a rotative platen, stops for arresting said platen, means for effecting a relative adjustment between certain of said stops to enable the platen to be turned for more or less than a full revolution as may be desired before the platen is arrested by said stops, a chain for moving certain of said stops, and means for enabling the platen to rotate independently of said stops.

13. In a typewriting machine, the combination of a rotative platen, two wheels one of which is turned by the platen, an endless band which passes around said wheels, a stop that is moved by said band, means coöperative with said stop to arrest the platen, and means whereby the platen may continue its movement after it is arrested by said stop and its coöperative means.

14. In a typewriting machine, the combination of a rotative platen, two wheels one of which is a driving wheel which is turned by the platen, an endless band which passes around said wheels, a stop that is moved by said band, means coöperative with said stop to arrest the platen, and means for effecting an operative connection or disconnection between said driving wheel and platen.

15. In a typewriting machine, the combination of a rotative platen, sprocket wheels one of which is a driving wheel which is turned by the platen, a sprocket chain which passes around said sprocket wheels, a stop carried by said chain, means coöperative with said stop to arrest the platen, and means whereby the platen may continue its rotation after it is arrested by said stop and its coöperative means.

16. In a typewriting machine, the combination of a rotative platen, sprocket wheels, one of which is a driving wheel turned by the platen, a sprocket chain which passes around said sprocket wheels, a stop carried by said chain, means coöperative with said stop to arrest the platen, and hand-actuated means operable at will for connecting and disconnecting said driving wheel and platen.

17. In a typewriting machine, the combination of a rotative platen, a platen shaft, wheels, one of which is a driving wheel on the platen shaft, an endless band that passes around said wheels, a stop carried by said band, means coöperative with said stop to arrest the platen, and means operable at will for operatively connecting said driving wheel to and for disconnecting it from said platen shaft.

18. In a typewriting machine, the combination of a rotative platen, a platen shaft, sprocket wheels, one of which is a driving wheel mounted on the platen shaft, a sprocket chain which passes around said sprocket wheels, stop devices for arresting said chain and platen, and means operable

at will to render the stop devices inoperative to arrest said platen.

19. In a typewriting machine, the combination of a rotative platen, a platen shaft, 5 sprocket wheels one of which is a driving wheel loosely mounted on the platen shaft, a sprocket chain which passes around said sprocket wheels, relatively adjustable stop devices for arresting said chain, and clutch 10 mechanism for connecting said driving wheel to and for disconnecting it from the platen shaft.

20. In a typewriting machine, the combination of a platen, a platen shaft, a platen 15 frame, sprocket wheels one of which is a driving wheel mounted on the platen shaft and the other of which is mounted on the platen frame, an endless sprocket chain which passes around said sprocket wheels, a 20 stop fixed to the sprocket chain, a pair of relatively adjustable stops on the platen frame which coöperate with the stop on the chain to arrest the platen, and hand actuated means operable at will to enable the 25 platen to turn beyond the positions where it is arrested by the coöperation of said stops.

21. In a typewriting machine, the combination of a platen, a platen shaft, a platen 30 frame, sprocket wheels one of which is a driving wheel loosely mounted on the platen shaft and the other of which is mounted on the platen frame, an endless sprocket chain which passes around said sprocket wheels, a stop fixed to the sprocket chain, a pair 35 of relatively adjustable stops on the platen frame which coöperate with the stop on the chain to arrest the platen, and a clutch operative to connect the driving wheel to or disconnect it from the platen shaft.

40 22. In a typewriting machine, the combination of a rotative platen, a pair of wheels adapted to rotate concurrently with the platen, an endless band which passes around said wheels, a rod or bar which extends 45 parallel with said band where it passes from one wheel to the other, relatively adjustable stops carried by said bar, certain of said stops being connected with said band, and means operable at will to enable the 50 platen to rotate freely beyond the positions where it is ordinarily arrested by the coöperation of said stops.

23. In a typewriting machine, the combination of a rotative platen, a platen frame, 55 a pair of wheels adapted to rotate concurrently with the platen, an endless band which passes around said wheels, a rod or bar which extends parallel with said band where it passes from one wheel to the other, 60 relatively adjustable stops carried by said bar; indicating means to aid in properly setting certain of said stops, certain of said stops being connected with said band, and a clutch for operatively connecting one of

said wheels to and for disconnecting it from 65 the platen.

24. In a typewriting machine, the combination of a rotative platen, a platen frame, a pair of sprocket wheels one of which is mounted concentrically with the platen, an 70 endless sprocket chain which passes around said wheels, a rod or bar fixed to the platen frame, relatively adjustable stops carried by said bar, indicating means to aid in effecting a relative setting of said stops, means 75 for connecting certain of said stops to said sprocket chain, and means for operatively connecting said chain to and for disconnecting it from the platen.

25. In a typewriting machine, the combination of a rotative platen, a platen shaft, a platen frame, a pair of sprocket wheels one of which is a driving wheel loosely mounted on the platen shaft, an endless sprocket chain which passes around said 85 wheels, a rod or bar fixed to the platen frame and extending parallel with said chain where it passes from wheel to wheel, two relatively adjustable stops carried by said bar, indicating means to aid in effecting a 90 relative setting of said stops, a third stop connected to said sprocket chain, and means for connecting said driving wheel to and for disconnecting it from the platen shaft.

26. In a typewriting machine, the combination of a rotative platen, a platen shaft, a platen frame, a pair of sprocket wheels one of which is a driving wheel loosely mounted on the platen shaft, an endless sprocket chain which passes around said 100 wheels, a rod or bar fixed to the platen frame and extending parallel with said chain where it passes from wheel to wheel, two relatively adjustable stops carried by said bar, indicating means to aid in effecting a relative 10 setting of said stops, a third stop connected to said sprocket chain, a clutch for connecting said driving wheel to and for disconnecting it from the platen shaft, and means for retaining the clutch against accidental displacement in either of the two 11 positions to which it may be moved.

27. In a typewriting machine, the combination of a rotative platen, an endless band which is adapted to move concurrently with the 12 rotative movement of the platen, and stop devices for arresting said endless band and platen.

28. In a typewriting machine, the combination of a rotative platen, wheels adapted 1 to turn concurrently with the platen, an endless band which passes around said wheels, stops which arrest the said band, means which enable the platen to continue its rotation after the stops have been brought 1 into coöoperative engagement, and means for effecting a relative adjustment of said wheels to take up slack in said band.

29. In a typewriting machine, the combination of a rotative platen, sprocket wheels adapted to turn concurrently with the platen, an endless sprocket chain which passes around said sprocket wheels, stops which co-operate with said chain to arrest it, means for enabling the platen to continue its rotation after the stops are brought into co-operative engagement, an eccentric which constitutes the pivot on which one of said sprocket wheels turns, and means for effecting a rotative adjustment of said eccentric to take up the slack of said chain.

30. In a typewriting machine, the combination of a rotative platen, sprocket wheels adapted to turn concurrently with the platen, an endless sprocket chain which passes around said sprocket wheels, an eccentric which constitutes the pivot on which one of said sprocket wheels turns, means for effecting a rotative adjustment of said eccentric to take up the slack of said chain, stops which co-operate with said chain to arrest it and a clutch for operatively connecting one of said sprocket wheels to and for disconnecting it from the platen.

31. In a typewriting machine, the combination of a rotative platen, a line spacing wheel therefor, stop devices for arresting said platen, certain of said stops having a rectilinear movement transmitted thereto by the platen, and a toothed clutch for connecting and disconnecting said platen and the rectilinearly moving stop, one member of said clutch having as many teeth as there are teeth in the line spacing wheel.

32. In a typewriting machine, the combination of a rotative platen, a platen frame, an endless band that is adapted to move concurrently with the turning movement of the platen, wheels around which said band passes, a bar that is fixed to the platen frame and which is parallel with the band where it passes from one wheel to the other, a fixed stop, and an adjustable stop on said bar, a scale on said bar and along which the said adjustable stop may be set, a stop carried by said band and which moves between the fixed and adjustable stops on said bar, and means which enable the platen to be rotated freely after the stops have been brought into co-operation.

33. In a typewriting machine, the combination of a rotative platen, a platen frame, an endless stop carrying band that is adapted to move concurrently with the turning movement of the platen, wheels around which said band passes, a stop carrying bar that is fixed to the platen frame and which has a part that is parallel with the band where it passes from one wheel to the other, and which also has a part that follows the curvature of the band as it passes around one of

said wheels, and means which enable the platen to be rotated after the stops have been brought into co-operation.

34. In a typewriting machine, the combination of a rotative platen, a flexible stop carrier, stopping means co-operative therewith to arrest the rotation of the platen, and means operable at will for operatively connecting the flexible stop carrier to and for disconnecting it from the platen.

35. In a typewriting machine, the combination of a rotative platen, a flexible stop carrier, stopping means co-operative therewith to arrest the rotation of the platen, and hand actuated means operable at will to enable the platen to continue its rotation after the platen has been arrested by the co-operation of the flexible stop carrier and stopping means.

36. In a typewriting machine, the combination of a rotatory platen, a flexible band connected with said platen, and movable when the platen is rotated, a stop movable with said platen and flexible band, and a relatively fixed stop for arresting the movements of the last recited three members.

37. In a typewriting machine, the combination of a rotatory platen, a flexible band, means for connecting said band operatively to said platen and for disconnecting it therefrom, a stop made movable by said band when the latter is connected to move with the platen, and means for arresting all of the foregoing parts when they have moved a predetermined extent.

38. In a typewriting machine, the combination of a rotatory platen, a movable stop therefor, a flexible band operatively connected to said platen for communicating motion to said stop, and other means for arresting said movable stop.

39. In a typewriting machine, the combination of a rotatory platen, a flexible band connectible to and disconnectible from said platen at will, and two co-operative platen-arresting stops, one movable simultaneously with said flexible band, and the other relatively fixed upon the platen frame.

40. In a typewriting machine, the combination of a rotatory platen, a flexible band, a pair of wheels with which said band co-operates, a stop connected to move in unison with said band, and a co-operating stop for arresting the rotation of the platen.

41. In a typewriting machine, the combination of a rotatory platen normally free to be rotated in either direction, and means connectible with said platen for arresting a backward rotation thereof, said means comprising a pair of band wheels, a flexible band, a stop controlled by and movable in unison with said band, and a relatively fixed co-operating stop.

42. In a typewriting machine, the combination of a rotatory platen, a band wheel connected to rotate therewith, a second band wheel, an endless band, a stop movable therewith, and a relatively fixed stop on the frame.

43. In a typewriting machine, the combination of a rotatory platen, a pair of band wheels connectible with and disconnectible therefrom, a flexible band traveling about said wheels, a stop carried by said band, a bar

for guiding said stop, and a relatively fixed stop.

Signed at the borough of Manhattan, city of New York, in the county of New York, and State of New York, this 17th day of 15 April A. D. 1908.
